UNITED STATES PATENT OFFICE.

LEWIS H. DORN, OF CARTHAGE, MISSOURI.

PERCH-POLE.

1,130,715.

Specification of Letters Patent. Patented Mar. 9, 1915.

Application filed November 19, 1913. Serial No. 801,855.

To all whom it may concern:

Be it known that I, LEWIS H. DORN, a citizen of the United States, residing at Carthage, in the county of Jasper and State of Missouri, have invented certain new and useful Improvements in Perch - Poles, of which the following is a specification, reference being had therein to the accompanying drawing.

This invention provides a roost or perch for chickens or other fowls that is arranged to contain insecticide and to diffuse it to the exterior at different places in order that it may be widely disseminated and act efficiently in destroying insects and the like.

It is an object of the invention to enhance the efficiency, lessen the cost, and increase the utility of devices of this character.

When read in connection with the description herein, the details of construction and arrangement of parts contemplated by the invention will be apparent from the accompanying drawing, forming part hereof, wherein an embodiment of the invention is disclosed for purposes of illustration.

While the embodiment shown now is considered a preferable one, it is to be understood that it is not the intention necessarily to be limited thereto in interpretation of the claims, as modifications within the scope of the claims can be made without departing from the nature and spirit of the invention.

Like reference-characters refer to corresponding parts in the views of the drawing, of which—

Figure 1 is a longitudinal sectional view of a portion of the perch-pole; Fig. 2 is an end view of the perch-pole; Fig. 3 is a transverse sectional view, on the line 3—3, Fig. 1; Fig. 4 is a transverse sectional view, on the line 4—4, Fig. 6; Fig. 5 is a view of the perch-pole in elevation, with parts broken away; Fig. 6 is a view of the pole-tube; Fig. 7 is a sectional view of an end-supporting stirrup; and Fig. 8 is a view thereof in elevation.

Having more particular reference to the drawing, 9 designates a perch-pole, which, preferably, is formed of a length of sheet metal rolled to substantially cylindrical shape, except at the ends, and having its longitudinal edges lapped, whereby a hollow body containing an insecticide-reservoir 10 is provided. Between the lapping edges of the material there is a slot opening to the

interior of the pole. For a short distance at each end, the pole is polygonal, preferably square, in cross section, and at each end the material is flared outwardly as a flange 11. A sheet-metal closing member 12 has its edges bent over the flange 11 and crimped down, as shown at 13, whereby a fluid-tight closure for the reservoir is formed. The end member is polygonal, preferably square, in cross-section.

To support the perch-pole at each end, there is provided a stirrup 14, which is formed of sheet metal. The stirrup comprises a web portion 15, corresponding in shape to the end of the pole, and it has its bottom and side edges slotted at the corners, as shown at 16, and turned over and inwardly to form lapping flanges 17 sufficiently removed from the web to permit the end member 12 to be slipped between them and the web. The upper portion of the web is extended substantially horizontally and then downwardly as flanges 18 and 19, respectively, which are adapted to engage the top of a member 20 of a chicken-house, rack, or the like, whereby the stirrup is fixedly supported, a nail, screw, or the like 21 holding the stirrup down in place. The end member 12 of the pole is slipped into the stirrup with its side and bottom edges under the flanges 17, whereby the pole is supported, and the angular formation of the parts prevents the pole from turning. When it is desired to remove the pole, it is lifted out of the stirrup at each end.

At intervals along the cylindrical portion of the perch-pole, it is wrapped with and encircled by absorbent wicking 22, a portion of which is led between the laps of the material and down to the bottom of the reservoir in the pole. The cylindrical portion of the pole and the wicking 22 are covered with medicated absorbent sheet material 23, which may be felt-paper wrapped around the pole. The absorbent covering 23 is protected by a sheath 24 of non-absorbent sheet material perforated to permit diffusion of insecticide. This sheath may be of comparatively hard fiber paper, sheet metal, or any other suitable non-absorbent material. Preferably the absorbent covering 23 and the sheath 24 are long strips of material helically wound on the pole.

In order to prevent insects from getting onto the perch-pole from the stirrup, the polygonal end portions of the pole are

wrapped with soft wicking 25, which extends through the laps of the pole down into the reservoir. This wicking is held in place by clamps 26.

5 A filling-tube 27, having a substantially fluid-tight hinged cap 28 on its upper end, leads into the reservoir at one of the polygonal ends.

10 A trunco-conical or funnel-shaped shield 29, flaring toward the end of the pole, is placed at such position on each end portion of the pole that it will extend over and protect the wicking 25 and the filling-tube 27 from the feet of fowls. The shield is held 15 in place by having a collar portion 30, which is placed around the end of the sheath 24, clamped by a band 31. The band is split and has depending ears 32, through which is passed a screw, bolt, or other suitable member 33 for drawing the band tightly around the collar 30. When the absorbent covering 23 and the sheath 24 are long strips helically wound on the pole, as in the preferred method of covering the pole, the band 20 31 serves to hold the ends of the strips as well as the shield.

Liquid insecticide is placed in the reservoir 10 through the filling-tube 27, and by absorption the wicking 25 and 22 and the 25 absorbent covering 23 are saturated with it, and it is diffused through the perforations of the sheath 24. In case the liquid runs over the tube, and when there is drip from the filling-receptacle, excess liquid is taken 30 up by the wicking 25. Liquid in excess of what can be absorbed by the wicking will make its way to the depending ears 32, which constitute an overflow-drip.

Having thus described my invention, what 40 I claim as new, and desire to secure by Letters Patent, is—

1. A perch-pole comprising a hollow cylindrical body formed of sheet material having its longitudinal edges lapping each other, and absorbent wicking encircling said pole and extending between the lapping portions to the interior of the pole.

2. A perch-pole comprising a hollow body having a slot laterally opening to its interior, and absorbent wicking encircling said pole and extending through said slot into the interior of the pole.

3. A perch-pole comprising a hollow body having a slot opening to its interior, absorbent wicking encircling said pole and extending through said slot into the interior of the pole, and an absorbent covering of sheet material on said pole enveloping the wicking thereon.

60 4. A perch-pole comprising a hollow body having a slot opening to its interior, absorbent wicking encircling said pole and extending through said slot into the interior of the pole, an absorbent covering of sheet material 65 on said pole enveloping the wicking thereon,

and a perforated sheath enveloping said covering.

5. A perch-pole comprising a hollow body, an absorbent covering of sheet material on said pole, means for conveying liquid from 70 the interior of the pole to said covering, and a perforated sheath enveloping said covering.

6. A perch-pole comprising a hollow body, a strip of absorbent sheet material helically 75 wound around said body and constituting a covering therefor, a strip of non-absorbent perforated sheet material helically wound over said covering, and a band near each end of said pole securing ends of said strips. 80

7. A perch-pole comprising a hollow body having near each end a slot opening to its interior, and soft wicking encircling the pole near each end and extending through one of said slots into the interior of said pole. 85

8. A perch-pole comprising a hollow body formed of sheet material having its longitudinal edges lapping each other and being polygonal in cross section at its ends and substantially cylindrical intermediate its 90 ends, the material being flared outwardly as a flange at each end, and at each end a closing member having its edges bent over the said flange.

9. A perch-pole comprising a hollow body 95 having near each end a slot opening to its interior, soft wicking encircling the pole near each end and extending through one of said slots into the interior of said pole, and on the pole a shield flaring toward the end 100 of the pole and extending over said wicking.

10. A perch-pole comprising a hollow body having near each end a slot opening to its interior, soft wicking encircling the pole near each end and extending through one of said slots into the interior of the pole, and a shield including a collar encircling the pole and a flaring portion extending therefrom toward the end of the pole and extending over the wicking, and a band clamping 110 said collar on the pole.

11. A perch-pole comprising a hollow body formed of sheet material having its longitudinal edges lapping each other, near 115 each end soft absorbent wicking encircling said pole and extending between the lapping portions into the interior of the pole, absorbent wicking encircling said pole at intervals intermediate the ends and extending between the lapping portions into the interior of the pole, a strip of absorbent sheet material helically wound around said pole intermediate 120 its ends and constituting a covering therefor, a strip of non-absorbent perforated material helically wound over said covering and constituting a sheath therefor, a shield including a collar encircling said pole near each end and surrounding and confining the ends of said covering and sheath 125 and having a flaring portion extending over 130

the soft wicking, and a band clamping said shield on the pole.

12. The combination of a perch-pole having an end polygonal in cross-section and having a terminal laterally-extending flange, and a stirrup comprising a web portion corresponding in shape to the end of the pole and having lapping flanges arranged to have

the flange of the pole seat between them and the web portion. ¹⁰

In testimony whereof I affix my signature in presence of two witnesses.
